UNITED STATES PATENT OFFICE.

FRANK KNIGHT, OF NEW HAVEN, CONNECTICUT.

DOOR OPENING AND CLOSING MECHANISM.

1,037,267.

Specification of Letters Patent.

Patented Sept. 3, 1912.

Application filed July 18, 1911. Serial No. 639,150.

To all whom it may concern:

Be it known that I, FRANK KNIGHT, a citizen of the United States, residing at New Haven, county of New Haven, State of Connecticut, have invented an Improvement in Door Opening and Closing Mechanism, of which the following is a specification.

This invention has for its general object to provide mechanism for automatically effecting the opening and closing of one or more doors or the like by the operation of a button or other device, or, preferably, by the operation of any one of a series of such devices suitably or conveniently located.

The more particular objects of the invention, together with means whereby the same may be carried into effect, will best be understood from the following description of one form or embodiment thereof illustrated in the accompanying drawings. It will be understood, however, that the construction described and shown has been chosen for illustrative purposes merely, and that the invention may be embodied in other forms without departing from the spirit and scope thereof.

In said drawings: Figure 1 is a plan view, partly broken away, of a door having opening and closing mechanism applied thereto, 30 the operating cylinder and its associated valve being shown in section on the line 1—1, Fig. 7. Fig. 2 is a detail section on the same plane as Fig. 1, of a portion of the operating cylinder and valve showing the 35 position of the parts when the door is open. Fig. 3 is a view similar to Fig. 2 but taken on the line 3—3, Fig. 7. Fig. 4 is a view, partly diagrammatic and partly in section, of the electromagnet, the circuit in which 40 said electromagnet is located and the controlling valve actuated thereby. Fig. 5 is a sectional view of the muffler and back pressure or exhaust valve. Fig. 6 is a sectional view of the inlet pressure regulating valve. Fig. 7 is a sectional view of the operating 45 cylinder valve. Fig. 8 is a side view, partly in section on the line 8—8, Fig. 4, of the controlling valve actuating means and containing also a diagrammatic representation of the signaling circuit. Figs. 9 and 10 are 50 sectional views on the lines 9—9 and 10—10, respectively, Fig. 4. Figs. 4 to 7, inclusive, collectively constitute a diagrammatic rep-

resentation of the controlling mechanism as a whole, while Fig. 1 shows more particularly the door operating mechanism controlled thereby.

For convenience the part operated is herein designated as a "door," although this term is intended to include such similar devices as windows, gates, and the like to which the apparatus is equally applicable, as will be obvious.

12 (Fig. 4) denotes an electromagnet, suitably located and supported, and energized 65 by an electric circuit comprising wires 13, 13 leading from a battery or other source of electric energy 14, said circuit being adapted to be closed by any one of a series of buttons or other circuit closing devices 15 arranged 70 at any convenient point or points. The armature 16 (Figs. 4 and 8) of the magnet 12 is pivoted upon any suitable support and is normally held away from the magnet by a spring 17. Pivoted, as by a screw 19, to the 75 armature 16, is a pawl 18 normally held in the position shown in full lines in Fig. 8 by a spring 20. The pawl 18 co-operates with a ratchet 21 having an even number of teeth, herein shown as eight, and rigidly secured to 80 or formed integral with the controlling valve 22, herein shown as a tapered turning plug held firmly seated in its casing 23 by a spring 24.

25 and 26 denote wires connected, respectively, with the armature 16 and valve casing 23, said wires constituting an electric circuit including a battery or other source of electric energy 27 and a signal or alarm device such as a bell 28. The arrangement 90 is such that when the pawl 18 is brought into contact with the ratchet 21 the circuit is closed and the signal or alarm device operated.

The valve 22 is provided with one or more 95 inlet passages 29 (see Figs. 4 and 9) and, in another plane, with an equal number of exhaust passages 30 (see Fig. 10). As herein shown there are two of each of these passages extending entirely through the 100 valve 22 at right angles to one another, the passages 29 being offset angularly with respect to the passages 30.

31 denotes a pipe leading from a source of fluid under pressure, such as compressed 105 air, and communicating with a port 32 in

the valve casing 23, which port is connected, in certain positions of the valve 22, by one or the other of the inlet passages 29, with a port 33 communicating with a pipe 34. The pipe 34 is continued in a pipe 35 having a branch 36 communicating with a port 37 in the valve casing 23, which port 37 is connected, in certain other positions of the valve 22, by one or the other of the exhaust passages 30, with the port 38 communicating with a pipe 39 leading to the muffler 40 (see Fig. 5). The arrangement is such that when the ports 32 and 33 are connected by one of the passages 29, communication between the ports 37 and 38 is broken and vice versa. This in the present instance is accomplished by arranging the ports 32, 33, 37 and 38 in the same plane and offsetting the passages 29 and 30 angularly as above described, but it will be obvious that a similar result may be effected by offsetting the ports 32 and 33 from the ports 37 and 38.

41 denotes an adjustable exhaust or back-pressure valve for controlling the admission of fluid from the pipe 39 to the chamber of the muffler 40, said fluid afterward escaping from said muffler through an outlet opening 42.

The pipe 35 (see Fig. 6) communicates with a fluid pressure regulator comprising a cylinder or casing 43 having a valve seat 44 coöperating with a valve 45 provided with a stem 46 secured to a piston 47 working in the cylinder 43. 48 denotes a spring 30 interposed between the piston 47 and a screw cap 49 by which the tension of said spring may be adjusted. With the parts in the position shown in Fig. 6 the valve 45 is open, providing communication between the pipe 35 and a pipe 50 leading from the regulator casing 43. Should the pressure in the casing 43 rise beyond a certain predetermined amount the piston 47 will be moved in opposition to the spring 48 to close the valve 45 and thereby shut off communication between the pipes 35 and 50. The pressure at which the valve 45 will close may be controlled by adjusting the cap 49 and consequently the tension of the spring 48.

50. The pipe 50 leads to the door or doors which it is desired to operate (there being one only shown in the drawings) and communicates at its end (see Fig. 7) with a nipple 51 projecting from the operating cylinder valve 52 (see also Figs. 1, 2 and 3). The valve 52 has an interior chamber 53 and is rigidly held, as by set screws 56, in arms 54 projecting from a bracket 55 secured to the door frame or other stationary support. The valve 52 is preferably of slightly tapered form to coöperate with the tapered bore of a sleeve 57 formed upon the head 58 of the operating cylinder 59, said valve and sleeve being held in close engagement by a spring 64. The valve 52 is provided with ports 60

and 61 communicating respectively with ports 62 and 63 in the cylinder head 58. 75 denotes a spring pressed check valve controlling communication between the chamber 53 and the port 61. The arrangement of the ports 60 and 62 is such that with the parts in the position shown in full lines in Fig. 1 the port 62 is in communication with the port 60, but when the parts are turned into the position shown in dotted lines in Fig. 1 and in full lines in Figs. 2 and 3 the port 62 is carried out of communication with the port 60.

65 denotes a piston in the cylinder 59, said piston being backed by a spring 66 and having a piston rod 67 pivoted at 68 to a lever 69. Said lever 69 is pivoted at one end to a bracket 70 secured to the door 71, and at the other end, at 72, to a radius arm 73 which, in turn, is pivoted at its opposite end, as at 74, to the bracket 55 or other stationary support on the door frame.

The operation of the apparatus is as follows: When it is desired to open the door 71, one of the buttons 15 is pressed, thereby closing the circuit through the battery 14 and the electro-magnet 12 and energizing said magnet, which thereupon attracts its armature 16, moving the same from the position shown in full lines in Fig. 8 to the position shown in dotted lines therein, and causing the pawl 18 to engage the ratchet 21 and turn the same through the space of one tooth. Engagement of the pawl 18 with the ratchet 21 closes the circuit through the wires 25 and 26, battery 27 and bell 28, causing said bell to be sounded to indicate the fact that the door is being operated. Turning of the ratchet 21 causes the valve 22 to be turned into the position shown in Figs. 4, 9 and 10, thereby carrying both of the passages 30 out of register with the ports 37 and 38 and connecting the ports 32 and 33 through one of the passages 29. Fluid pressure from the pipe 31 is thereupon admitted through the pipe 34 to the pipe 35 and thence through the fluid pressure regulator and pipe 50 to the chamber 53 of the operating cylinder valve 52, from which the same passes through the ports 60 and 62 to the interior of the operating cylinder 59. The piston 65 is thereupon moved in opposition to the spring 66, causing a movement of the lever 69 from the position shown in full lines in Fig. 1 to the position shown in dotted lines therein, and opening the door 71. During the opening movement of the door, the cylinder 59 is turned on the valve 52 from the position shown in full lines in Fig. 1 to the position shown in dotted lines therein, and in full lines in Figs. 2 and 3. This movement carries the port 62 out of register with the port 60, thereby trapping the fluid under pressure in the cylinder 59 and holding the door open until 130

the controlling mechanism is again operated to close said door. When it is desired to close the door one of the buttons 15 is again pressed, thereby again energizing the magnet 12 and causing another operation of the armature 16 to turn the ratchet 21 through the space of one tooth and again sound the alarm 28. This last turning of the ratchet 21 causes the valve 22 to turn from the position shown in Figs. 4, 9 and 10 into a position in which communication between the ports 32 and 33 is shut off and communication established through one of the passages 30 between the ports 37 and 38. The pressure on valve 45 of the regulator is thereby reduced, whereupon spring 48 unseats said valve. The spring 66 thereupon operates to return the piston 65 to the position shown in Fig. 1 and close the door 71, the fluid under pressure in the cylinder 59 passing through the ports 63 and 61, lifting the check valve 75 and passing through the chamber 53 to the pipe 50, thence through the pressure regulator casing 43, pipe 35, branch 36, port 37, passage 30, port 38, pipe 39 and valve 41 to the muffler 40 from which it may escape to the atmosphere or be exhausted in any other way through the outlet opening 42.

In order to regulate the speed at which the door will be opened the cap 49 of the fluid pressure regulator may be adjusted to vary the pressure of the fluid admitted to the operating cylinder 59. Similarly in order to adjust the speed at which the door will be closed the back pressure or exhaust valve 41 may be set to permit the fluid under pressure to be exhausted from the cylinder 59 under the action of the spring 66 at any desired rate.

It will be observed that the door 71 may, if desired, be opened by hand at any time without interference by the operating mechanism described. On the other hand when said door has been automatically opened by the operation of any of the circuit closing devices 15 it must be closed by a second operation of one of these devices, since, as above stated, when the door has been completely opened by admitting fluid pressure to the cylinder 59 the port 62 is moved out of register with the port 60, thereby holding the door in open position until the valve 22 has been turned to permit such fluid pressure to be exhausted through the passages 30 in said valve.

From the foregoing it will be seen that the passages 29 and 30 in the valve 22 are alternatively operative so that at each successive fractional turn of said valve by means of the pawl 18 and ratchet 21 the door will be alternately opened and closed.

If it be desired to cause the simultaneous operation of a plurality of doors, each of said doors may be provided with operating

mechanism similar to that described and the pipe 50 formed with a corresponding number of branches, as will be obvious.

Having thus described my invention I claim:

1. The combination with a movable element, of a fluid pressure operating device therefor, and a valve for said operating device, the latter being provided with a pivot member encircling said valve, said valve and operating device being provided with means that cause the fluid pressure to be trapped when the movable element reaches the limit of its movement. 70

2. The combination with a movable element, of a fluid pressure operating device therefor, and a valve for said operating device, said operating device being supported upon and inclosing said valve, said valve and operating device being adapted to 85 trap the fluid pressure when the movable element reaches the limit of its movement.

3. The combination with a movable element, of a fluid pressure operating device therefor, and a valve for said operating 90 device, the latter being provided with a pivot member encircling said valve, said valve and operating device having co-operating parts arranged to be out of register so that the pressure is trapped in the operating 95 device when the movable element reaches the limit of its movement.

4. The combination with a door, of a fluid pressure operating device for said door, a stationary valve for said device having 100 inlet and exhaust ports communicating with said device, and a check valve between said ports.

5. A door operating device comprising a fluid pressure motor including a stationary 105 valve and a cylinder pivotally mounted thereon, the cylinder and valve being provided with co-operating inlet and exhaust ports, means carried by the valve and actuated by the fluid pressure therein for controlling said ports, a spring pressed piston in the cylinder, and door swinging means actuated by the piston. 110

6. A door operating device comprising a fluid pressure motor including a rotary controlling valve provided with inlet and exhaust ports, manually controlled means for operating the valve step by step, and means for trapping the fluid pressure in the motor when the door reaches the limit of 120 one of its movements. 116

7. In a device of the character described, the combination of fluid pressure operated mechanism for actuating a door, a valve for said mechanism provided with inlet and exhaust ports, and means carried by the valve and actuated by the fluid pressure therein for controlling said ports. 125

8. A door operating device comprising a fluid pressure motor including a stationary 130

4

valve, a cylinder having a sleeve surrounding said valve, said valve and said sleeve having complementary tapering surfaces, the sleeve and valve being provided with coöperating 5 inlet and exhaust ports, means for holding said tapered surfaces in closed engagement, a spring pressed piston in the cylinder, and door swinging means actuated by the piston.

9. A door operating device comprising a 10 fluid pressure motor including a stationary valve, a cylinder having a sleeve mounted to oscillate on said valve, the cylinder and valve being provided with coöperating inlet and exhaust ports, means carried by the 15 valve and actuated by the fluid pressure therein for controlling said ports, a spring pressed piston in the cylinder, and door swinging means actuated by the piston.

10. A door operating device comprising a 20 fluid pressure motor including a stationary valve provided with a longitudinal cham-

ber, and a cylinder pivotally mounted on said valve, the cylinder and valve being provided with inlet and exhaust ports, and a check valve in said chamber between said 25 ports.

11. A door operating device comprising a fluid pressure motor including a stationary valve having a longitudinal chamber and a cylinder pivotally mounted on said 30 valve, the cylinder and valve being provided with coöperating inlet and exhaust ports, a speed regulating device communicating with one end of said chamber, and means carried by the valve and actuated by the fluid pressure 35 therein for controlling said ports.

In testimony whereof I affix my signature in presence of two witnesses.

FRANK KNIGHT.
